US00D363977S

United States Patent [19]**Streit**[11] **Patent Number:** **Des. 363,977**[45] **Date of Patent:** ****Nov. 7, 1995**[54] **CONNECTOR BOX FOR TUBE**4,888,453 12/1989 Blasko ..... 174/71 R X
5,022,685 6/1991 Stiskin et al. ..... 285/419[75] Inventor: **Bernard Streit**, Anteuil, France*Primary Examiner*—Lou Zarfas[73] Assignee: **Sofanou S.A.**, Clerval, France*Assistant Examiner*—E. Watterson[**] Term: **14 Years***Attorney, Agent, or Firm*—Merchant, Gould, Smith, Edell,
Welter & Schmidt[21] Appl. No.: **18,594**[57] **CLAIM**[22] Filed: **Feb. 10, 1994**The ornamental design for a connector box for tube, as
shown and described.[30] **Foreign Application Priority Data****DESCRIPTION**

Aug. 17, 1993 [FR] France 934337

FIG. 1 is a perspective view with shading of the invention
in an open position;[52] U.S. Cl. ..... **D23/263**FIG. 2 is a view like FIG. 1 except taken from the bottom;
FIG. 3 is a view like FIG. 1 except it is an opposite
perspective;[58] **Field of Search** D23/263, 264,
D23/265; 285/156, 419, 903; 174/71 R,
135FIG. 4 is a bottom plan view;
FIG. 5 is a side view, the opposite side being a mirror image
thereof; and,
FIG. 6 is a top plan view.[56] **References Cited**
